Filed May 1, 1970, Ser. No. 22,750

Term of patent 14 years

Int. Cl. D12—11

U.S. Cl. D90—8

FIG. 2

FIG. 1 is a front perspective view of a sidewalk bicycle showing my new design; and

FIG. 2 is a rear perspective view of the design.

In FIGS. 1 and 2 the entire tire tread design has been only partially shown; and in FIG. 1 the rear stand is in the up position, whereas in FIG. 2 it is shown in the down position.

I claim:

The ornamental design for a sidewalk bicycle, substantially as shown and described.
